M. R. HARRISON,
METHOD OF MAKING REINFORCED RECEPTACLES,
APPLICATION FILED APR. 5, 1920.

1,419,048.

Patented June 6, 1922.

Fig. 3. *b* *a* Inventor:
Mary R. Harrison,

UNITED STATES PATENT OFFICE.

MARY R. HARRISON, OF BOSTON, MASSACHUSETTS, ASSIGNOR TO EDWARD H. ANGIER,
OF FRAMINGTON, MASSACHUSETTS.

METHOD OF MAKING REINFORCED RECEPTACLES.

1,419,048.

Specification of Letters Patent. Patented June 6, 1922.

Application filed April 5, 1920. Serial No. 371,831.

To all whom it may concern:

Be it known that I, MARY R. HARRISON, a citizen of the United States, and resident of Boston, in the county of Suffolk and State 5 of Massachusetts, have invented certain new and useful Improvements in Methods of Making Reinforced Receptacles, of which the following is a specification.

This application is a continuation of my 10 application filed October 2, 1916, Serial No. 123,255, so far as relates to subject matter common to both.

This invention relates to sheet material for enclosing heavy or bulky articles, and 15 the chief object is to provide material for this purpose which is economical to produce and is effective for many uses especially the manufacture of strong envelopes.

To make strong envelopes or bundle-wrapping sheets, it has long been customary to adhesively unite paper and cloth the latter being more or less closely woven according 20 to the particular uses to which the sheet material is to be put. Owing to the comparative cost of cloth suitable for the purpose, attempts have been made to make envelopes 25 of reinforced paper consisting of two sheets of paper with intervening strands of cord or twine, the two sheets being adhesively 30 united. Such attempts have been unsuccessful for several reasons one of which is that the twine, to possess sufficient strength, must be of such size that the blanks can not be successfully died out and then creased and 35 folded in an envelope-making machine, and twine of that size would result in the presence of such ridges on the surface which would have to be used when addressing the envelope that clear addressing is difficult if 40 not impossible.

In carrying out my invention, I preferably employ a single thickness of paper having thin flat unwoven tapes adhesively secured to that surface of the paper which is to be 45 the inside when the envelope or other container is completed. I emphasize envelopes because my improved sheet material is particularly well qualified for the manufacture of an effective economical substitute for the 50 present expensive cloth-lined envelopes.

Of the accompanying drawings:

Fig. 1 represents a sheet of the material, said figure also indicating how ordinary envelope blanks may be economically cut there- 55 from.

Fig. 2 represents an envelope blank creased and ready to be folded.

Fig. 3 represents a section on line 3—3 of Fig. 1, on an enlarged scale.

Fig. 4 represents a complete envelope 60 ready to receive an enclosure.

The paper *a* may be of any kind. The reinforcing strands *b* are preferably made of thin, flat, unwoven tapes, such as narrow strips of "Kraft" paper, gummed on one 65 surface, or that which is known as wrapping tape, consisting of a plurality of fine threads or fibers which are stuck together side by side. This material is sometimes known as "advertising tape" because merchants use it for tying up packages, the tape bearing the name and address of the merchant, and sometimes other printed matter. It is obtainable in various colors. I prefer plain white for white paper, but what some 70 might call artistic effects could be obtained by employing a variety of colors.

By the employment of a machine such as that in my Patent 1,195,951, granted Aug. 22, 1916, that is, by the employment of so 80 much of such machine as feeds a web of paper in the direction of its length and applies parallel longitudinal strands thereto, I produce such material as shown in Figure 1 of the present drawing. I find that by 85 moistening the paper, no adhesive other than what is carried by the tape itself as the latter is manufactured, is necessary. Or the paper *a* while on its way through the machine, may have stripes of an adhesive 90 applied thereto and the flat tapes simply be guided onto those stripes and the whole subjected to pressure. The tapes are parallel with each other and with the edges of the paper web and are simply stuck to the paper. 95

By employing such material I obtain great strength by width instead of thickness, and cause no such ridges as result from using ordinary twine or string having substantially the same strength. The width of the strands *b* is such as to confine between them and the paper all the adhesive that is necessary to firmly and permanently connect them. Ordinary thread or string, which is of course round in cross section, can not confine enough 100 adhesive to do this. And this flat tape material can be die-cut, and can be folded or bended around corners, more readily than round string or twine, and is not so liable to be engaged by other objects or articles, 110

and separated from the paper. In other words it clings much more closely to the paper than ordinary string or twine, and the entire sheet material is thinner or flatter, and the smoothness of the address-receiving surface of the paper is but slightly interrupted.

By cutting blanks from the material as indicated in Figure 1, so that the stays *b* cross all four fold creases substantially at an angle of 45 degrees as shown in Figure 2, and then folding in the usual way, an envelope such as shown in Figure 4 is produced.

It will now be understood that the sheet material as described is cheaper and of less weight than that now used for making the ordinary cloth-lined envelope. The economy is due not only to the smaller quantity of textile material, and dispensing with any weaving operation, but also to the use of much less adhesive since there must be a film of adhesive over the entire surface when cloth is employed. It is also cheaper and of less weight than reenforced paper consisting of triple-thick material (two of paper and an intervening layer of glue) and strings.

Ordinary twine or string can not be used in the manner in which I employ the flat tape because if fine it is impossible to locate enough glue between it and the paper to hold it in place, and if large enough to accommodate more glue it interferes with creasing and folding and addressing. By employing flat strands, they can be very thin and still have enough glue between them and the paper to secure them firmly.

Instead of employing previously made unwoven tape of the kind described, I may form such tape on the paper *a* by so guiding a plurality of fine threads that they will be laid on the paper in groups, with an adhesive securing said fine threads together and to the paper.

Most paper is so made that its tensile strength is greatest in the direction of the length of the web. In other words its "grain" as it is called is lengthwise of the web. When I employ paper for the stays or strands *b*, I preferably first coat a web of strong-grained paper with an adhesive and after the latter is dry then cut it into long narrow strips (say $\frac{1}{8}$ inch wide) and coil said strips, after which the strips may be applied to

the paper *a* in the same manner as hereinbefore described, preferably moistening only the adhesive-coated surfaces of the strips *b*.

Of course the "advertising tape" referred to has its grain in the direction of its length, and the same is true of paper strips or strands such as just described. Therefore, when the strands are arranged as shown in Figures 2 and 4, each fold crease of an envelope is crossed by strands the grain of which is longitudinal, and therefore best capable of reinforcing the folds of articles made from reenforced sheets of the kind described, and illustrated in Figure 1.

I do not limit myself to the manufacture of the kind of articles usually understood as envelopes, as my invention is applicable to other receptacles such as paper bags or boxes.

I also do not limit myself to combining the thin flat strands with previously made paper as they may be introduced in a web of pulp during the manufacture of paper in an ordinary paper-making machine, as explained in Letters Patent No. 1,325,091, granted to me December 16, 1919, from which paper so made and reenforced the blanks such as described will be cut.

Having now described my invention, I claim:

1. The method of making reenforced paper for folded receptacles, consisting in securing to a web of paper a plurality of separate spaced flat textile strands, and cutting blanks from said web in a manner to cause the strands to cross the blanks at an acute angle to the lines required for folding the blanks to receptacle form.

2. The method of producing blanks for making folded paper receptacles, consisting in securing to a web of paper a plurality of spaced reinforcing textile strands, and then cutting blanks therefrom at an angle of substantially 45° to said strands.

3. The method of producing blanks for making folded paper receptacles, consisting in securing to a web of paper a plurality of spaced groups of fine threads, each group having its threads close together, and then cutting blanks from said web at an angle of substantially 45° to the groups of threads.

In testimony whereof I have affixed my signature.

MARY R. HARRISON.

Certificate of Correction.

It is hereby certified that in Letters Patent No. 1,419,048, granted June 6, 1922, upon the application of Mary R. Harrison, of Boston, Massachusetts, for an improvement in "Methods of Making Reinforced Receptacles," an error appears requiring correction as follows: In the printed specification the residence of the assignee is erroneously given as "Framington, Massachusetts," whereas said residence should have been given as *Framingham, Massachusetts*, as shown by the records of assignments in this office; and that the said Letters Patent should be read with this correction therein that the same may conform to the record of the case in the Patent Office.

Signed and sealed this 11th day of July, A. D., 1922.

[SEAL.]

KARL FENNING,

Acting Commissioner of Patents.
